UNITED STATES PATENT OFFICE.

EVERETT P. LARSH, OF DAYTON, OHIO.

SHORT-CIRCUITING DEVICE FOR COMMUTATORS.

Application filed December 6, 1921. Serial No. 520,342.

To all whom it may concern:

Be it known that I, EVERETT P. LARSH, a citizen of the United States, residing at Dayton, in the county of Montgomery and State of Ohio, have invented certain new and useful Improvements in Short-Circuiting Devices for Commutators, of which the following is a specification.

This invention relates to electric motors and more particularly to a short circuiting or operation changing device for alternating current motors of the repulsion-induction type, by which the motor is automatically changed from a repulsion starting condition to an induction running condition and vice-versa, in accordance with variations of speed.

The object of the invention is to simplify the structure as well as the means and mode of operation of such circuit changing devices whereby they will not only be cheapened in construction, but will be more efficient in use, automatic in operation, uniform in action, automatically controlled, and unlikely to get out of repair.

A further object of the invention is to provide improved means operated by centrifugal tendency by which the commutator bars are automatically connected with a common electrical conductor which will promptly respond to variations of speed above and below a predetermined rate of rotation.

A further object of the invention is to provide a short circuiting or current changing device, which will have a shifting movement insuring perfect electrical contact, in which this shifting action will be further effected under yielding pressure thereby obviating any chatter or vibration and the incident arcing and burning of the contact surfaces.

A further object of the invention is to provide means for controlling the movement of the short circuiting or current changing members whereby their movement to effect the alternation of the motor from repulsion to induction operation and vice-versa, will be effected by a quick movement in either direction.

A further object of the invention is to provide such a short circuiting or current changing device which will be compact, of few parts, and having no pivot joints, nor indirect movement, but in which the current

controlling devices are directly operated by centrifugal tendency.

With the above primary and other incidental objects in view as will more fully appear in the specification, the invention consists of the features of construction, the parts and combinations thereof, and the mode of operation, or their equivalents, as hereinafter described and set forth in the claims.

Referring to the drawings, Fig. 1 is a longitudinal sectional view of an electric motor to which the present invention has been applied. Fig. 2 is a detail view showing the particular construction of the circuit closer illustrated in Fig. 1 in its operated or short circuiting position. Figs. 3 and 4 illustrate a modification of the short circuiting device shown in Figs. 1 and 2, and illustrate the inoperated and operated positions of the short circuiting element, adapted to make a butt contact with the commutator bar. Figs. 5 and 6 illustrate the inoperative and operative positions of a further modification of the construction shown in Figs. 3 and 4. Figs. 7 and 8 illustrate a further modification of the controlling means for the short circuiting devices, and also a modification in the short circuiting slug to facilitate its engagement upon the elastic retaining ring. Fig. 9 is a detail view of the elastic retaining ring with a series of contact slugs supported thereon.

Like parts are indicated by similar characters of reference throughout the several views.

The structure of the electric motor per se, forms no part of the present invention, which pertains wholly to the short circuiting means for the commutator bars, by which the motor is caused to operate alternately as a repulsion motor and an induction motor.

An alternating current, repulsion-induction motor of the single phase type to which the present invention is particularly adapted is one which as the name indicates, starts as a repulsion motor and as the speed approaches its normal or maximum rate of rotation automatically changes its character, and runs as an induction motor. Briefly described it consists of a field or stator of laminated toothed construction having a single winding thereon connected to the supply circuit and a progressively wound armature or rotor with a commutator engaged by

brushes during the starting or "repulsion" period together with speed controlled devices for short circuiting the armature windings thru the commutator after the 5 armature has attained a predetermined speed, which speed controlled means in some instances lifts the brushes from the commutator simultaneously with the short circuiting operation. There is no electrical connection 10 between the stator and the rotor. The currents in the stator create an alternating flux which reacts on the rotor and induces its rotation. This type of motor, therefore, starts as a simple repulsion 15 motor without compensating or auxiliary windings and operates as a repulsion motor until the rotor or armature approaches a synchronous speed or one commensurate with the windings, whereupon the speed controlled 20 devices operate to automatically short circuit the armature winding thru the commutator. Thus the motor is automatically transformed from a repulsion type into an induction motor having what is essentially 25 a squirrel cage rotor. It is the improvement of the speed operated governing or short circuiting device which forms the subject matter of the present invention. One of the advantages of a machine of this type is that it 30 is inherently a constant speed motor having a high starting torque with low current consumption or minimum current surge. The straight repulsion motor without compensation gives the most efficient starting 35 torque possible while the single phase induction rotor with the squirrel cage armature or its equivalent affords the most efficient motor when running.

A repulsion-induction type of motor combines 40 these most desirable qualities in a single machine. As it possesses such high starting torque characteristics it is well adapted for operating machinery which starts under full load, as pumps, air compressors, and grinding mills. Requiring no 45 starter they are adapted for automatic control, or distance operation. They start quickly and operate quietly and smoothly.

The above is offered merely to facilitate a 50 thorough understanding of the purpose of the invention, and with no intent nor desire that it shall in any way be construed as limiting or restricting the application or scope of the invention.

55 Referring to the drawings, 1 is the motor frame or housing, in which is located the annular stator 2 within which rotates the rotor 3, carried upon the shaft 4, mounted in suitable bearings 1^a in the opposite ends of the frame or housing. As shown in the drawings, the stator is of laminated form, while the rotor comprises the usual laminated core carrying a series of windings or coils (not shown in the drawing), the several coils being connected to corresponding

commutator bars 5. The commutator comprises a plurality of the bars 5 suitably mounted upon and insulated from a head 6, and insulated or electrically isolated one from the other. The commutator comprising the head 6 and electrically separated commutator bars carried thereby is mounted upon the shaft 4 and rotates therewith together with the rotor 3. That is to say, the rotor, the shaft and the commutator 70 form a single rotating element, as is ordinary in electric motors. Carried by a suitable annular collar or supporting ring 7 mounted in one of the end frames, are two brush holders 8 only one of which is 80 shown in the drawings, which carry brushes 9, interconnected one with the other and bearing upon the periphery of the commutator. Such is the usual form of motor to which the present invention is applied. 85

The short circuiting device forming the subject matter hereof comprises a conductor collar 10, slidably mounted upon the shaft 4 adjacent to the commutator. This conductor disc 10 is of concave or dished 90 formation, having at its center and surrounding the shaft 4 an inwardly flanged boss 11. This central boss 11 is of such extent that it engages the insulating head 6 of the commutator and forms a stop to limit 95 the approach of the outer edge of the disc 10 toward the terminal faces of the commutator bars 5. The conductor disc 10 is pressed inwardly or toward the commutator by a helical spring 12 internosed between the in-turned flange of the central boss 11 of said disc and a stop collar 13 fixed upon the rotor shaft 4. As shown in Figs. 4 and 5, this collar 13 may form a support or bearing for 100 the disc 10 upon which the disc slides to and from the commutator. The inturned flange of the central boss of this disc may also have a sliding bearing upon the shaft 4. These bearings may be quite loose, and there will be but little friction or wear at these 110 bearing points.

The intermediate or web portion of the disc 10 is inclined or concave to form a cam surface against which the centrifugally controlled conductor slugs operate in their outward movement to afford a wedging action, which eventually shifts the conductor disc outward against the tension of the retracting spring 12. The ends of the commutator bar project beyond the lateral face of the head 6, and are beveled or inclined on their inner side, as at 14 in a direction oppositely disposed relative to the inclination of the conductor collar 10. The overhanging ends of the contact bar 5 afford contact surfaces for the centrifugally controlled conductor slugs with which said slugs make both butt and wiping contact.

Located intermediate the conductor disc 10 and the terminal face of the commutator 115

is a series of radially disposed conductor slugs 15 of a substantially trapezoidal form. The number of these slugs greatly exceeds that of the commutator bars, there being 5 preferably an average of one and a half to two conductor slugs 15 for each commutator bar. The slugs 15 have each a slotted opening 16 therein thru which extends an elastic retainer shown in Fig. 9 as two close 10 coils of an evolute spring 17. The slugs 15 are strung upon the elastic retainer 17 closely together in a bead like fashion, whereby upon contraction of the elastic retainer 17, they are drawn into close association 15 one with the other. The series of slugs assembled upon the retaining ring 17 are located within the disc 10 intermediate the disc and the insulating head 6 of the commutator against which the perpendicular inner faces of the slugs are pressed by the retraction of the disc 10 under the influence 20 of the spring 12.

The conductor slugs 15 are oppositely beveled or substantially V-shaped adjacent to 25 their outer edges to agree with the oppositely disposed inclined faces of the disc 10, and commutator bars 5. The slugs 15 must have a wedging action between the non-yielding inclined surface 14 on the commutator bar, 30 and the inclined face of the conductor disc 10. It is to be noted by reference to Fig. 1, that the inclination 14 of the conductor bar 5 is located at a somewhat greater distance from the shaft 4 than the inclination of the 35 conductor disc 10. Thus during the initial movement of the slugs 15, the inclined face thereof acts only on the disc 10, to force the disc outward against the tension of its spring 12. There is somewhat less resistance to the 40 initial movement of the slugs 15 than is met with upon engagement of the slugs with the inclined contact face 14. As the slug 15 engages the contact face 14 of the commutator bar, it is directed slightly outward or laterally in unison with its radial movement 45 under the influence of the camming action of the face 14, and against the tension of the spring 12. Its outward movement, however, is retarded by the inclined face 14 with 50 which it makes a wiping contact in addition to its butt engagement therewith, the necessary pressure of the contacting surfaces of the slugs and commutator bars being insured by the resistance of the conductor disc 10, 55 and its spring 12.

It will be understood that the rings 17 while possessing sufficient tension to retract the slugs 15 when the rotor is at rest or operated at a sub-normal speed, this tension 60 is not sufficient to materially resist the outward movement of the slugs under the influence of centrifugal tendency.

While the elastic ring 17 may comprise a simple wire coil or a flexible cable, as 65 shown and described in my prior and co-

pending application Serial No. 363,402, filed March 5, 1920, of which invention the present construction is a continuation in part, the ring 17 is preferably a flat strap spring as shown in the drawing. In order to insure more uniform operation of the slugs upon such ring, the ends of the ring are preferably though not necessarily reduced to feather edges, in order that they may afford no obstruction to the sliding movement 70 of the slugs thereover. The flat strap spring is formed into a convolute coil, the convolutions of which closely contact one upon the other. To insure a close adherence of the ends of such coil, in order that they may 75 not form obstructions or engage the slug, the flat spring is initially coiled in one direction, and then before being used, it is recoiled in the same direction, but with the inner and outer ends transposed, whereby the 80 original inner convolution, becomes the outermost, and the outer convolution becomes the inner course of the completed ring. Thus the tension or resiliency of the 85 spring material is utilized to cause the ends of the coiled spring to conform closely to the succeeding convolutions thereof. That is to say, the inner convolution has an expansive tendency, while the outer convolution or end of the spring tends to contract in the completed retaining ring.

So long as the motor operates at a low rate of speed, the centrifugal tendency is not sufficient to overcome the inertia of the slugs. However, as the speed increases, the slugs 15 tend to move outward, expanding the retaining rings 17, and exerting a camming pressure of the inclined faces 18 upon the inclined or concave web or face of the disc 10. This camming action or wedging effect tends to increase the pressure of the contact of the slugs 15 upon the face of the commutator. As the speed and with it the centrifugal tendency increases, this camming 100 pressure upon the disc 10 exerts sufficient force to move the disc 10 outwardly against the tension of its retracting spring 12, thus permitting the slugs to move radially outward until they have moved off of the insulating head 6 and into contact with the terminal faces of the commutator bars 5. These slugs 15 thus electrically bridge the individual commutator bars 5 with the common conductor disc 10. It will be understood 105 that the retaining ring 17 is not necessarily a part of the short circuiting shunt. In fact, so far as the essential operation of the device is concerned, the retaining member 17 may be of non-conductive material. The circuit is completed from each commutator bar thru a slug 15 to the common conductor disc 10, thence to another commutator bar, so that all the commutator bars are interconnected one with the other thru the disc 10 and intervening slugs 15. This 110 115 120 125 130

bridging of the individual commutator bars 5, and the conductor disc 10 common to all the bars interconnects the armature windings one with another and the armature now 5 becomes in effect, a squirrel cage rotor.

Some constructors have thought it necessary or at least advisable to lift the brushes from contact with the commutator to prevent wear. However, the wear of the 10 brush and commutator is so slight as to be negligible. The destruction of brushes heretofore attributed to wear has in fact been due to burning of the brush, thru arcing between the brush and commutator. The 15 constant arcing or sparking of the brush upon the commutator burns the surface of the brush away rather than wears it away. Inasmuch as when the commutator bars are electrically interconnected one with the 20 other thru the disc 10 or short circuited, no arcing can occur between the brushes and the commutator, it has not been found necessary to lift the brushes or to separate them from the commutator bars.

25 As the speed of the rotor decreases and the centrifugal tendency becomes less effective, the conductor slugs 15 are retracted thru the combined tendency of the helical elastic retainer 17 and the pressure of the 30 inclined web or face of the disc 10, under the influence of the retracting spring 12. This retracting tendency causes the slugs 15 to move inward passing in such movement 35 from the conductor bars 5 to the insulating head 6, thereby breaking the contact between the commutator bars and the disc 10. This returns the rotor to the influence of the 40 brushes 9 and the windings or coils connected with the separated commutator bars 5, whereby the motor again operates under 45 repulsion influence.

While the elastic or expandible retainer 17 formed as shown, of two helical coils is 50 desirable, other forms of flexible connection 45 may be employed. However, the retainer may be omitted, and the slugs assembled side by side intermediate the disc 10 and 55 commutator entirely independent of each other. The slugs are sufficient in number and sufficiently closely associated that they 60 cannot become materially disarranged, and the camming pressure of the disc 10 under the influence of the retracting spring 12 may 65 be utilized to return the slugs to their normal or central positions.

The construction as heretofore described 65 is capable of various modifications, several 70 of which have been illustrated in Figs. 3 to 8 inclusive. In Figs. 3 and 4 there is shown 75 a modification in which in lieu of the inclined face 14, the commutator bars 5 are 80 extended at right angles to the face of the head 6 to form an overhanging annular 85 flange upon the commutator upon the inner 90 face of which the slugs abut, when moved

to their outermost position. In this construction, the form and operation of the conductor disc 10 and spring 12 are the same as heretofore described, and the construction differs from that of Figs. 1 and 2 70 in that the contact of the slugs with the commutator bar is a flat abutting engagement and not a wiping or wedging contact as previously described.

In Figs. 5 and 6 there is shown a further 75 modification differing from those previously described in that the head 6 is formed with an overhanging inclined cam face 20, engaged by a correspondingly beveled face upon the slugs 15, whereas the common conductor disc 10^a forms without its inclination or concavity as before described. In this form of device the contact bars 5 overhang the slugs in the same manner as in Figs. 3 and 4. However, the slugs ride radially 80 upon the disc 10, in the same manner that they ride upon the head 6 in the construction heretofore described. However, the disc 10^a yields against its tension spring under the 85 influence of the engagement of the slugs 15 with the inclined face 20, thus resisting to some extent the outward movement of the slugs under centrifugal tendency. At the 90 limit of the outward movement, the slugs 95 abut upon the overhanging ends of the contact bars 5.

In Figs. 7 and 8 there is shown a further 100 modification in which there is employed a stationary disc or collar 21 and a yielding collar or disc 10^b which corresponds to the common conductor discs 10 and 10^a of the previous constructions. The slugs 15 are located between the discs 21 and 10^b. The disc 10^b is formed with a concave 105 or inclined web portion, engaged by a corresponding inclined face upon the slugs to afford a camming action by which the disc or collar 10^b is pressed laterally against the tension of the spring 12. In its outward 110 position the slugs 15 contact the inner side of the overhanging commutator bars 5 as shown in Fig. 8. In Figs. 7 and 8 there is shown a further modification in which the eye or opening in the slugs 15, thru which 115 is extended the elastic ring 17, extending laterally to the edge of the slug. In other words, the opening in the slug is in the form of a slot, having a somewhat reduced 120 orifice enabling the slugs 15 to be assembled laterally upon the ring or coil 17.

A further development and amplification 125 of the subject matter of the present invention is illustrated and described, and the invention more broadly claimed in co-pending application Serial No. 669,716, filed October 20, 1923, to which reference is to be had.

From the above description, it will be apparent that there is thus provided a device of the character described possessing the 130

particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language 10 more or less specific as to structural features, it is to be understood that the invention is not limited to the specific details shown, but that the means and construction herein disclosed comprise but one of 15 several modes of putting the invention into effect, and the invention is therefore claimed in any of its forms or modifications within the legitimate and valid scope of the appended claims.

20 Having thus described my invention, I claim:

1. In a short circuiting device for motors, a plurality of centrifugally actuated weights arranged circumferentially of the armature 25 shaft of the motor and operable radially to effect the electrical interconnection of the commutator bars of the motor, and a flat involute spring resisting the radial movement of the weights and against the yielding 30 resistance of which the weights move under centrifugal influence to effect the short circuiting of the motor.

2. A short circuiting device for electric 35 motors, a commutator and a disc relatively movable in axial relation against yielding resistance, the adjacent faces of said disc and commutator being converging in a radial direction, a plurality of interposed wedge shape centrifugally actuated circuit 40 closer members having marginal bearing surfaces extending in parallel relation with the adjacent faces of the disc and commutator upon which they have sliding contact and commutator bar extensions into engagement 45 with which the circuit closers are movable against the yielding resistance of the converging faces of the commutator and disc.

3. A short circuiting device for electric 50 motors comprising a commutator and a disc in relatively spaced relation, a cam face on the commutator, centrifugally actuated circuit closer members having contact faces agreeing with the commutator cam face interposed between the commutator and the 55 disc, and engaging the cam face to afford yielding resistance to their movement, and commutator bar extensions engaged by the circuit closers when extended under centrifugal influence.

60 4. A short circuiting device for electric motors comprising a commutator and a disc in relatively spaced relation, a cam face on the disc, centrifugally actuated wedged shaped circuit closers interposed between 65 the disc and commutator having angularly

arranged contact surfaces slidingly engaging the cam face and commutator to afford yielding resistance to their movement, and commutator bar extensions engaged by the circuit closers when extended under centrifugal influence.

5. A circuit closing device for electric motors, comprising two relatively movable members arranged in spaced relation, one of said members peripherally converging toward the other, centrifugally actuated wedged shape circuit closers interposed between the said members and having converging lineal bearing surfaces engaging the converging members in their movement to afford yielding resistance to their radial movement, and commutator bar extensions engaged by the circuit closers extended under centrifugal influence.

6. In a short circuiting device for motor 65 commutators, an annular series of weights arranged circumferentially of the motor shaft and revoluble therewith, said weights being radially movable under centrifugal influence to effect the short circuiting of 70 the motor commutator and a radially expandible and contractible coiled spring the successive convolutions of which are arranged substantially concentrically relative to the annular series of weights engaging 75 with the weights and acting to restrain their radial movement.

7. In a short circuiting device for electric 80 motors, the combination with a plurality of commutator bars to be electrically connected 100 one with another, of a series of centrifugally controlled weights, a flat elastic band upon which the weights are carried, said band being expandible and contractible in accordance with centrifugal influence of the 85 weights, said weights when in their operated positions effecting the electrical interconnection of the commutator bars one with another.

8. In a short circuiting device for motors, 90 the combination with a plurality of commutator bars to be electrically connected one with another, of a series of centrifugally controlled weights, each having an eye formed therein and having an entrance slot leading to said eye, an annular elastic retaining ring, engageable within said eye thru the entrance slot, said ring being expandible under centrifugal influence of the weights, 95 the weights when in operated positions effecting the electrical interconnection of the commutator bars one with another.

9. In a short circuiting device for motors, 100 the combination with a plurality of commutator bars to be electrically connected one with another, of a series of centrifugally controlled weights, an annular elastic ring acting to restrain the movement of the weight under centrifugal influence comprising a flat strip wound upon itself into 105

convolute formation the outer convolutions of which possess greater contractive tendency than the inner convolutions, whereby the ends of the strip are made to closely adhere to the adjacent convolution, said ring being expansible under centrifugal influence of the weight to permit radial movement of the weights into the air operations positions to effect the electrical interconnection of the 10 commutator bars one with another.

10. In a short circuiting device for electric motors, the combination with a plurality of commutator bars to be electrically connected one with another, of a series of centrifugally controlled weights, an annular elastic ring having engagement with the weights comprising a flat strip wound upon itself into a convolute formation, expansible under centrifugal influence of the weights, 15 said weights when in their operated positions effecting the electrical interconnection of the commutator bars one with another.

11. In a short circuiting device for motor commutators, an annular series of 20 weights arranged circumferentially of the motor shaft and revoluble therewith, said weights being radially movable under centrifugal influence to effect the short circuiting of the motor commutator, said 25 weights having registering eyes formed therein, and access slots extending from said eyes to the marginal edges of the

weights, and a retaining member insertable through such slots into the eyes.

12. In a short circuiting device for motor commutators, an annular series of 35 weights arranged circumferentially of the motor shaft and revoluble therewith, and movable by centrifugal influence to effect short circuiting of the motor commutator, 40 and an annular contractile band yieldingly resisting the movement of said weights and comprising a succession of concentric convolutions extending circumferentially of 45 said band, the convolutions being maintained under opposing tension under which the outer convolution tends to contract and the inner convolution tends to expand whereby the ends of the band are made to closely conform to the adjacent convolutions. 50

13. In a short circuiting device for motor commutators of the character described, an annular series of weights circumferentially arranged relative to the motor shaft, 55 said weights being radially movable under centrifugal influence to effect the short circuiting of the commutator, and a flat involute spring common to all of said weights against the yielding resistance of which the weights are radially movable.

In testimony whereof, I have hereunto set my hand this 26th day of June A. D. 1920.

EVERETT P. LARSH.
